LOCKING MECHANISM

Albert Sidney Kendrick, Wolverhampton, England, assignor to The Yale & Towne Manufacturing Company, Stamford, Conn., a corporation of Connecticut

Application September 24, 1945, Serial No. 618,083
In Great Britain September 20, 1944

10 Claims. (Cl. 70—38)

1

This invention relates to locking mechanism applicable for example to the locking of the shackle of a padlock but capable of application to the locking of bars or sliding or rotary members incorporated in mechanism generally.

An object of the invention is to provide an improved and simplified locking device providing a positive locking action of the member until released by the actuation of a key operating element.

As applied to a padlock it is preferred that the locking means according to the invention provides a lock for both the heel and toe of the shackle.

According to the invention the locking means comprises a rotary element or bolt having a part adapted to engage within a slot or lie in the path of a surface of the bar or sliding or rotary member whereby it obstructs the movement of said member, key actuated means being provided for rotating the element to remove the obstruction.

In its application to the locking of the shackle of a padlock the rotary locking element is preferably provided with locking formations co-operating with recesses on surfaces on the heel and toe of the shackle.

The invention also consists in a padlock comprising a hinged or spring operated shackle wherein a single bolt is provided, and interengaging means on the bolt and heel and toe of the shackle for deadlocking the shackle.

In the accompanying drawings—

Figure 1 is an elevation, partly in section, of a padlock incorporating the invention,

Figure 2 is a perspective view of the lock with the case removed,

Figure 3 is a perspective view of a housing for the locking bolt,

Figure 4 is a perspective view showing the locking bolt and the actuating plug of the lock mechanism,

Figure 5 is an elevation of a padlock shackle and bolt according to a modification,

Figures 6 and 7 are elevations showing the invention applied to a pivoting shackle,

Figures 8 and 9 are elevations of a modified arrangement,

Figures 10 and 11 are views showing a further modification,

Figures 12, 13 and 14 are views showing modified forms of returning springs,

Figure 15 shows a modified form of bolt, and

Figures 16 and 17 show the application of the

2

invention to the locking of a pair of displaceable rods.

In carrying the invention into effect according to one convenient mode by way of example as applied to a padlock in which the shackle has a sliding movement, the toe $1a$ and heel $1b$ of the shackle 1 are provided respectively with slots or recesses 2 and 3 into which bolt projections 4 and 5 on a rotary bolt 6 are adapted to engage in the locked position, see Figures 1 and 2. The rotary bolt 6 is located within a housing 7 which is riveted or otherwise secured to the cylinder body 8 .

Rotation of the rotary bolt is effected by a cam 15 or projection 9 on the cylinder plug 10 engaging the edge 11 of an opening 12 in the bolt into which opening the cam 9 projects.

Rotation of the bolt to the unlocked position causes the tensioning of a torsion spring 13 , one end of which is anchored to the bolt by a pin 14 , the other end being connected to a pin 15 extending through slots 16 in the bolt and secured to the bolt housing 7 . Pin 15 also locates the bolt axially in the housing 7 .

The heel $1b$ of the shackle extends into a recess 17 in the cylinder body at the bottom of which a spring 18 is provided by which the shackle is moved outwardly to the open position when released by the bolt 6 . Outward movement of the shackle is limited by a bar 19 engaging a longitudinal slot 20 in the heel of the shackle. Inward movement of the shackle is limited by the engagement of the toe $1a$ with a seating 21 on the cylinder body. The lock case 22 engages positioning lugs 23 on the cylinder body to which it is secured by rivets passing through holes in the case, housing and cylinder body.

On rotation of the plug 10 by the appropriate key, the rotary bolt 6 is rotated to remove the projections 4 and 5 from the recesses 2 and 3 of the shackle, whereupon the shackle is opened by the spring 18 . When the shackle is returned to the locked position, the bolt is rotated by the torsion spring 13 to bring the projections 4 and 5 into locking engagement with the recesses 2 and 3 .

With the improved rotary bolt, the lock cannot be "shocked" open, and when the shackle is locked, the case cannot be removed to expose the mechanism, even should the rivets 23 be removed. The security of the padlock thus depends entirely upon the keyway mechanism.

It will be obvious that instead of the cylinder type of lock, lever type or any other known keyway security mechanism may be employed.

According to a modification, see Figure 5, the heel 24 of the shackle may be provided with two recesses 25, 26 the rotary bolt having corresponding projections 27, 28 whereby a three point lock is provided for the shackle.

When applied to a pivoting shackle 29, see Figures 6 and 7, the rotary locking element or bolt 30 engages a recess 31 in the toe 32 of the shackle and at the opposite end of the bolt provides an obstruction to an abutment 33 on the adjacent heel 34. When the bolt is moved to the unlocking position the abutment 33 is adapted to pass through a groove 35 in the end face of the bolt.

According to a modification, see Figures 8 and 9, a radial tooth 36 may be provided on the pivoted heel of the shackle adapted to engage an axially extending surface or projection 37 on the locking bolt or element when in the locking position. In the unlocked condition the tooth 36 passes through a groove 38 in the end face of the bolt.

In order to guard further against "shocking" the locking bolt into the release position, the bolt 39, Figures 10 and 11, may be provided with a radial projection 40 which in the locked position engages behind a spring loaded plunger 41 mounted on the adjacent end face of the plug 42. In the return movement of the locking bolt the radial projection 40 is adapted to depress the spring loaded plunger 41 to pass the plunger and again become locked.

Instead of the coiled torsion spring, a compression spring 43, see Figure 12, seated partly in a recess 44 in the bolt and in a recess 45 in an adjacent stationary part 46 may be used. Again a feather spring 47, see Figure 13, of hair pin form may engage a flat 47a on the bolt or a feather spring 48, Figure 14, may be used as a torsion spring, one end being connected to the bolt 49, the other end being connected to a relatively stationary part 50.

According to another arrangement, see Figure 15, the locking bolt may be made in two parts, 51, 52, one part 51 having a stem 53 around which a spring 54 is coiled. One end of the spring engages a relatively fixed member while the other engages a lug 55 on another part 52 which is adapted to seat on a squared end 56 of the stem.

Instead of a tube for the locking bolt a solid bar having the required end formation may be provided.

The invention is not confined to its application to a padlock but may be utilised in connection with the locking of rods or bars against longitudinal or rotary movement. Thus as illustrated in Figures 16 and 17 a pair of bars 57 and 58 adapted for longitudinal movement, either in the same or in opposite directions, have a rotary locking bolt 59 located therebetween. The bolt is provided with diametrically opposite end projections 60 adapted in its locking position to engage in recesses 61 in the rods. When the bolt 59 is turned to the unlocked position the rods 57, 58 may slide through the spaces between the projections 60.

The bolt may be operated with a key actuated plug as in the preceding examples of the invention and may be provided with spring return means or positively moved to the locking position by the key.

Instead of a common locking bolt for both bars 57 and 58, independent bolts may be provided.

The invention may also be applied to the dead-locking of rotary members by the arrangement of a rotary bolt element so that the locking pro-

jection or projections thereof may engage in recesses in the rotary member.

I claim:

1. In a lock of the class described, a casing having openings in its upper end for the legs of a sliding shackle, a tubular sleeve rotating in juxtaposed relation to the upper end of said casing and between said shackle legs, lugs formed as integral parts of said sleeve through the cutting of the surface of said sleeve, and notches in each of said shackle legs into which said lugs extend to lock said shackle, the rotation of said sleeve withdrawing said lugs from said notches to release said shackle.

2. In a lock of the class described, a casing having openings in its upper end for the legs of a sliding shackle, a tubular sleeve rotating in juxtaposed relation to the upper end of said casing and between said shackle legs, lugs formed as integral parts of said sleeve through the cutting of the surface of said sleeve, notches in each of said shackle legs into which said lugs extend to lock said shackle, the rotation of said sleeve withdrawing said lugs from said notches to release said shackle, a key plug rotatable in said casing, and a cam surface on said key plug for rotating said sleeve to release said shackle.

3. In a lock of the class described, a casing having openings in its upper end for the legs of a sliding shackle, a tubular sleeve rotating in an axis transverse to said shackle legs and between said shackle legs, lugs formed as integral parts of said sleeve through the cutting of the surface of said sleeve, notches in each of said shackle legs into which said lugs extend to lock said shackle, the rotation of said sleeve withdrawing said lugs from said notches to release said shackle, a key plug rotatable in said casing in an axis parallel to said shackle legs, and a cam surface on said key plug extending into a slot in said sleeve for rotating the sleeve to release said shackle.

4. In a lock of the class described, a casing, a shackle slideable relatively to said casing, a tubular sleeve rotating in said casing and relatively to said shackle, a lug formed as an integral part of said sleeve, a notch in said shackle into which said lug extends to lock said shackle, the rotation of said sleeve withdrawing said lug to release said shackle, means fixed to said casing extending into said sleeve through a slot therein, and a torsion spring secured between said means and sleeve to rotate said sleeve into a locking position.

5. In a lock of the class described, a casing, a shackle slideable in said casing, a tubular sleeve rotating in said casing relatively to said shackle, a lug formed as an integral part of said sleeve, a notch in said shackle into which said lug extends to lock said shackle, the rotation of said sleeve withdrawing said lug from said notch to release said shackle, a pin fixed to said casing and extending into said sleeve through a slot therein, a pin extending transversely of said sleeve and fixed thereto, and a torsion spring secured at its ends to said pins to rotate said sleeve into locking position.

6. In a lock of the class described, a casing, a movable bolt in said casing, a tubular sleeve rotating in said casing, a lug formed as an integral part of said sleeve, said bolt having a notch into which said lug extends to lock said bolt against movement, the rotation of said sleeve withdrawing said lug from said notch to release said bolt, a key plug rotatable in said casing in an axis transverse to the axis of said sleeve, and a cam surface on said key plug extending into a slot in

said sleeve for rotating the sleeve to release said bolt.

7. In a lock of the class described, a casing, a shackle slidable in said casing, a tubular sleeve rotating in an axis transverse to said shackle, a lug formed as an integral part of said sleeve, said shackle having a notch into which said lug extends to lock said shackle, the rotation of said sleeve withdrawing said lug from said notch to release said shackle, a key plug rotatable in said casing in an axis parallel to said shackle, and a cam surface on said key plug extending into a slot in said sleeve for rotating the sleeve to release said shackle.

8. In a lock of the class described, a casing having openings for the legs of a sliding shackle, a tubular sleeve rotating in said casing and between said shackle legs, lugs formed as integral parts of said sleeve, and notches in each of said shackle legs into which said lugs extend to lock said shackle, the rotation of said sleeve withdrawing said lugs from said notches to release said shackle.

9. In a lock of the class described, a casing having openings for the legs of a sliding shackle, a tubular sleeve rotating in said casing and between said shackle legs, lugs formed as integral parts of said sleeve, notches in each of said shackle legs into which said lugs extend to lock said shackle, the rotation of said sleeve withdrawing said lugs from said notches to release said shackle, means fixed to said casing extending into said sleeve through a slot therein, a torsion spring secured between said means and sleeve to rotate said sleeve into a locking position, a key plug rotatable in said casing, and a cam surface on said key plug for rotating said sleeve to release said shackle.

10. In a lock of the class described, a casing having openings for the legs of a sliding shackle, a tubular sleeve rotating in said casing and between said shackle legs, lugs formed as integral parts of said sleeve, notches in each of said shackle legs into which said lugs extend to lock said shackle, the rotation of said sleeve withdrawing said lugs from said notches to release said shackle, means fixed to said casing extending into said sleeve through a slot therein, a torsion spring secured between said means and sleeve to rotate said sleeve into a locking position, a key plug rotatable in said casing, and a cam surface on said key plug extending into a slot in said sleeve for rotating the sleeve to release said shackle.
